JOHN A. HENDRICKS, OF LONG BEACH, CALIFORNIA, ASSIGNOR OF ONE-HALF TO
WILBERT MAPLE, OF LONG BEACH, CALIFORNIA.

PUMPING DEVICE.

Application filed June 24, 1925. Serial No. 39,351.

This invention appertains to novel means for pumping oil or water from deep wells and the primary object of the invention is to provide a novel device of the permanent 5 nature which can be incorporated with an ordinary type of well casing for facilitating the raising of oil liquid from deep wells which have ceased flowing; the improved device entirely eliminating the necessity of 10 providing pump plungers and the like.

Another object of the invention is to provide novel means for lifting water and oil from a deep well embodying means for raising the liquid from the well by compressed 15 fluid, such as gas or air, novel means being provided for directing the flow of the compressed gas into the well casing and the discharge pipe.

A further object of the invention is the 20 provision of a novel distributor for the gas for insuring of the correct distribution of the gas through the medium being raised.

A further object of the invention is the provision of a novel mixture arranged above 25 the distributor for breaking up the gas into small particles for insuring the correct mingling thereof with the liquid being raised and to direct the gas and the liquid being raised toward the center of the outlet pipe.

A still further object of the invention is 30 to provide means for elevating liquid from a deep well pump which has flow under its own pressure, which will be durable and efficient in use, one that will be simple and

35 easy to manufacture and one which can be incorporated with a standard well casing at a small cost.

With these and other objects in view, the 40 invention consists in the novel construction, arrangement and formation of parts, as will be hereinafter more specifically described, claimed, and illustrated in the accompanying drawings, in which drawings:

Figure 1 is a longitudinal section through 45 the novel pumping apparatus,

Figure 2 is a horizontal section through the pump taken on the line 2—2 of Figure 1 looking in the direction of the arrows,

Figure 3 is a horizontal section taken on 50 the line 3—3 of Figure 1 looking in the direction of the arrows, showing the construction of the distributor.

Referring to the drawings in detail, 55 wherein similar reference characters designate corresponding parts throughout the

several views, the letter A generally indicates the novel liquid elevating means, which comprises the well casing 5 which extends into the bottom of the well. At the lower end of the casing 5 below the level of the oil or other liquid, which is being raised, is disposed a packer 6 which supports a casing 7 arranged concentrically within the well casing 5 in spaced relation thereto. The lower end of the casing 7 is also disposed below the level of the oil and is preferably made into a pair of sections 8 and 9 connected together by a suitable sleeve or coupling 10. The lower section 9 constitutes the casing for the distributor 11, as will be hereinafter more fully described, while the upper sections 8 constitute a casing for the mixer 12 as will be also hereinafter more fully described. Connected to the upper end of the section 8 of the casing 7 is an outlet pipe 13, a reducing coupling 14 being employed for connecting the said outlet pipe with the upper end of the casing 8. This outlet pipe 13 extends through a suitable casing head 15 exteriorly of the well. The packer 6, head 15, well casing 5, and the casing 7 and outlet pipe 13 define a gas chamber 16, which will also be hereinafter more fully described. The extreme upper end of the well casing 5 is provided with the compressed fluid inlet 17 and the compressed fluid inlet 17 and the compressed medium is adapted to flow into the chamber 16 and is prevented from going into the bottom of the well by the packer 6.

The distributor 11 embodies a cylinder 18 which is arranged in spaced concentric relation to the section 9 of the casing 7 and the upper and lower ends of the cylinder 18 is provided with flanges or heads 19 and 20 for engaging the inner surface of the said section 9 forming a fluid pipe connection therewith. The upper end of the cylinder 18 is provided with a plurality of relatively fine perforations 21, as is the flange or head 19. This distributor is preferably below the oil level in the well, and the section 9 is provided with the compressed air inlet openings 22 for permitting the flow of the compressed gas or other medium into the chamber 23 defined by the cylinder and section 9. The expanding medium used will then flow through the openings 21 in relatively small particles into the oil or water being raised. The gas passing through the openings 21 will mix with oil to a certain extent, but

is likely to form large pockets or bubbles in the oil. When the large pockets or bubbles are formed in the oil a relatively large quantity of gas is needed to lift the oil, 5 but if the gas is mixed thoroughly into the oil to form a plurality of minute bubbles, a relatively large quantity of oil will be lifted with the gas. The mixer 12 functions to break up the gas into fine particles and to 10 also direct the oil and mixed gas toward the axial center of the casing so as to prevent the gas from following up the side of the casing. The mixer 12 includes a plurality of spaced concavo-convex shaped disks 15 25 disposed in the section 8 of the casing 7 and these disks 25 are provided with the plurality of minute mixing openings 26. Any desired number of these disks 25 are provided and are held together in their desired relation by a coupling rod 27. A ring 20 28 can be employed for supporting the lowermost disks.

When oil is being raised, it is preferred to use a compressed gas, while if water is 25 being raised, steam or air will serve the purpose. A suitable compressor can be mounted at the well hole for forcing the compressed fluid into the chamber 16 and a separator receives the fluid forced from the 30 well to separate the gas from the liquid. The compressed gas is found to separate very readily from the oil and that is the prime reason in using the compressed gas with the oil.

35 In use of the improved liquid pumping device, the compressed medium is allowed to flow through the inlet nipple 17 as heretofore stated down the chamber 16, through the openings 22 into the chamber 20 23 then into the distributor through the minute openings 21 up through the oil, through the mixer and out of the outlet pipe 13 to the separator.

40 From the foregoing description, it can be seen that a simple device has been provided for forcing a fluid from a well which has sufficient pressure to rise a certain distance in the well but not enough to flow from the well.

45 Changes in details may be made without departing from the spirit or the scope of this invention, but—

What I claim as new is:

1. In a well pump, a casing, an inner casing disposed in concentric relation to the first casing, a packer connecting the lower end of the casing to the first casing, a well casing head connecting the casings together, means for introducing a compressed fluid 50 into the upper end of the first mentioned casing, a compressed fluid distributor in the lower end of the inner casing receiving the compressed medium and a mixer arranged in the inner casing above the distributor.

55 2. In a well pump, a well casing, an inner

casing disposed within the well casing in spaced concentric relation thereto, means connecting the inner casing with the well casing at the lower end thereof, a well casing head connecting the well casing with the inner casing, a compressed gas inlet carried by the upper end of the well casing, means for distributing the compressed gas with the liquid being raised, and means disposed above the distributor in the inner casing for thoroughly mixing the gas with the liquid. 70 75

3. In a well pump, a well casing, an inner casing disposed in the well casing in spaced concentric relation thereto, means connecting the lower end of the inner casing to the well casing, a casing head connecting the upper end of the inner casing to the well casing, a cylinder disposed in the lower end of the inner casing in spaced concentric relation thereto, means connecting the opposite end of the cylinder to the inner casing, the upper end of the cylinder having a plurality of openings therein, means for permitting the flow of compressed gas from the well casing into the cylinder, means for introducing a compressed gas into the upper end of the well casing, and a mixer for the gas and liquid being elevated above said cylinder. 80 85 90

4. In a well pump, a well casing, an inner casing arranged within the well casing in spaced concentric relation thereto, means connecting the opposite ends of the inner casing to the well casing, means introducing a compressed gas into the upper end of the well casing, means for permitting the flow of the gas into the lower end of the inner casing, means for distributing the gas throughout the liquid being elevated, and means for mixing the gas with the liquid being elevated including a plurality of spaced perforated 100 105 disks arranged above the distributor and disposed within the inner casing.

5. In a well pump, a well casing, an inner casing disposed within the well casing in spaced concentric relation thereto, a packer supporting the inner casing having fluid pipe connection with the well casing, an outlet pipe, a casing head carried by the upper end of the well casing and engaging the outlet pipe, a reducing coupling connecting the outlet pipe with the upper end of the inner casing, means for introducing a compressed gas to the upper end of the well casing, means for permitting the flow of the gas into the lower end of the inner casing, a cylinder arranged in spaced concentric relation to the inner casing disposed in the lower end thereof, flanges connecting the opposite ends of the cylinder with the inner casing the cylinder and upper flange having a plurality of minute openings therein through which the compressed gas is adapted to flow, and a mixer arranged in the casing above the cylinder including a plurality of equi-distantly 110 115 120 125 130 spaced concavo-convex perforated disks, and

means holding the disks in position in said inner casing.

6. In a well pump, a well casing having an inlet adjacent its upper end for introducing compressed gas thereinto, an inner casing disposed in the well casing in spaced concentric relation thereto and having a plurality of openings adjacent its lower end, a cylinder arranged concentrically within the lower portion of the said inner casing and having a plurality of perforations positioned above the openings in the said inner casing, and a plurality of equidistantly spaced concavo-convex perforated disks arranged within the inner casing above the said cylinder.

7. In a well pump, the combination with a well casing having an inlet adjacent its upper end for introducing compressed gas

thereinto, and an inner casing disposed within the well casing in spaced concentric relation thereto and having a plurality of openings adjacent its lower end, of a cylinder arranged concentrically within the lower portion of said inner casing, flanges carried by the opposite ends of the cylinder for connecting the same with the inner casing, the cylinder and upper flange having a plurality of minute openings therein disposed above the openings in the said inner casing, a plurality of equi-distantly spaced concavo-convex perforated disks, and means for holding the disks in properly spaced position within the said inner casing above the said cylinder.

In testimony whereof I affix my signature.
JOHN A. HENDRICKS.
